(57) **CLAIM**

The ornamental design for an electrocardiogram article, as shown and described.

DESCRIPTION

FIG. 1 is a top perspective view of an electrocardiogram article, showing our new design;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a side elevation view thereof; and,

FIG. 8 is a side elevation view thereof.

The broken lines are included for illustrating portions of the electrocardiogram article that form no part of the claimed invention.

1 Claim, 6 Drawing Sheets---
